(57) **CLAIM**

The ornamental design for “television set,” as shown and described.

DESCRIPTION

FIG. 1 is a front, right, top perspective view of a television set in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right-side elevation view thereof; and,

FIG. 7 is a left-side elevation view thereof.

Subject matter shown in dashed lines in FIGS. 3, 6 and 7 is for illustrative purposes only and forms no part of the claim design.

1 Claim, 5 Drawing Sheets
